STORING AND OPERATING AID FOR SAFETY PINS

William H. Drake, Carpinteria, Calif.

Application April 19, 1955, Serial No. 35,570

Term of patent 14 years

(Cl. D86—10)

Fig. 2.

Fig. 1.

Fig. 1 is a perspective view substantially from the side of the storing and operating aid for safety pins showing my new design.

Fig. 2 is a perspective view thereof.

The opposite side of Fig. 1 is substantially similar to the one shown.

I claim:

The ornamental design for a storing and operating aid for safety pins, substantially as shown and described.

No references cited.
